Danthoisi

[11] Patent Number: Des. 424,070

[45] Date of Patent: ** May 2, 2000

[54] LAWNMOWER

5,619,845 4/1997 Bruener et al. 56/11.9

[75] Inventor: **Jean-Claude Danthoisi**,
Chavagnes-les-Redoux, FrancePrimary Examiner—Sandra L. Morris
Attorney, Agent, or Firm—Michael Best & Friedrich LLP[73] Assignee: **Ariens Company**, Brillion, Wis.[57] **CLAIM**[**] Term: **14 Years**

The ornamental design for a lawnmower, as shown and described.

[21] Appl. No.: **29/091,213**

DESCRIPTION

[22] Filed: **Jul. 23, 1998**

FIG. 1 is a perspective view of a lawnmower showing our new design;

[51] LOC (7) Cl. **15-03**

FIG. 2 is a top plan view thereof;

[52] U.S. Cl. **D15/14**

FIG. 3 is a rear elevational view thereof;

[58] Field of Search D15/10, 14-18;
56/6, 11.9, 16.7, 17.1, 17.4, 17.5, 202,
255, 320.1, 320.2

FIG. 4 is a right side elevational view thereof, the left side view being a mirror image of that shown; and,

[56] **References Cited**

FIG. 5 is a front elevational view thereof.

U.S. PATENT DOCUMENTS

The bottom of the lawnmower is not visible in its normal or intended use. Therefore, the bottom view is not a matter of ornamental concern, and has been omitted from the drawings.
